[57] CLAIM

The ornamental design for a combined personal computer mouse and digitizing stylus device for use with a drawing board accessory, as shown and described.

DESCRIPTION

FIG. 1 is a left side rear perspective view of a combined personal computer mouse and digitizing stylus device for use with a drawing board accessory showing our new design;

FIG. 2 is a top plan view of FIG. 1;

FIG. 3 is an right side elevation view of FIG. 1;

FIG. 4 is a left side elevation view of FIG. 1;

FIG. 5 is a bottom plan view of FIG. 1;

FIG. 6 is an elevation front end view of FIG. 1; and,

FIG. 7 is an elevation rear end view of FIG. 1.

The connecting cord shown in alternate positions in the views is shown in broken lines for illustrative purposes only and forms no part of the claimed design.
